UNITED STATES PATENT OFFICE.

JAMES PETER DONOVAN, OF GEORGETOWN, KENTUCKY.

RAILROAD-TIE.

1,078,666.

Specification of Letters Patent. Patented Nov. 18, 1913.

Application filed January 23, 1913. Serial No. 743,812.

To all whom it may concern:

Be it known that I, JAMES PETER DONOVAN, a citizen of the United States, residing at Georgetown, in the county of Scott and State of Kentucky, have invented certain new and useful Improvements in Railroad-Ties; and I do hereby declare the following to be a full, clear, and exact description of the invention, such as will enable others skilled in the art to which it appertains to make and use the same.

This invention relates to railroad ties, and it more particularly relates to a combination of cement and metal elements united to form a pliable railroad tie.

An object of the invention is to provide a railroad tie of this character, in which the danger of breakage, between the railway rails, is eliminated.

A still further object is to provide metal railway rail seats permanently united with the concrete elements of the tie.

A still further object is to provide connecting bars for the cement or concrete elements, said connecting bars being yieldable.

A still further object is to provide reinforcing elements which also serve to hold said rail seats in position.

A still further object is to provide a rail seat member which may be stamped in a single piece from sheet metal, and at one operation.

Other objects and advantages will be hereinafter more clearly set forth in the specification and pointed out in the claims.

In the accompanying drawings, which are made a part of this application, Figure 1 is a plan view of one of my improved ties having fragmental portions of railway rails seated thereon. Fig. 2 is a side elevation of the construction shown in Fig. 1. Fig. 3 is a vertical longitudinal section through a fragment of one of my improved ties and the rail seat thereof. Fig. 4 is a sectional view on the line 4-4 of Fig. 3. Fig. 5 is a sectional view on the line 5-5 of Fig. 3. Fig. 6 is a perspective view of my improved rail seat. Fig. 7 is a fragmental detail view of a slightly modified form of my rail seat, and, Fig. 8 is a vertical longitudinal section through a fragment of my improved railway tie, and embodying the modification shown in Fig. 7.

Referring to the drawings, in which similar reference numerals designate corresponding parts throughout the several views, the

two base portions 10, which may be made from cement or from a composition of cement with other suitable materials, are connected by a pair of horizontal connecting bars 11. These connecting bars are preferably twisted at their middle portions 12, through an angle of 90°, as shown, thereby providing a yieldable element between the adjacent ends of the base members, so that the tie will yield at its middle portion, instead of breaking, under excessive weight and jar on the rail seats 13 and these bars extend to the bottom of the base portions so as to protect the latter from being broken by the tamping tools when ballast is being tamped thereunder. The connecting bars are secured to the base portion 10 by means of bolts 14, which extend through pipe sections 15, which are embedded in the base portions and extend horizontally therethrough. These pipe sections are preferably flared at their ends 16, thereby being prevented from working or jarring out of the apertures in which they are seated. The base members may be reinforced in any desired and proper manner, as by means of metal rods or bars 17.

The rail seat is preferably integral with approximately vertical side flanges 18 and approximately vertical depending tongues 19, which are apertured at 20 for the reception of a combined anchoring and reinforcing element 21 or 22. This reinforcing member may be formed either as shown in Fig. 3 or as in Fig. 8, and in either event it is placed in engagement with the apertures 20, and the cement base is thereafter molded around the anchoring member, the tongues 19 and the base of the flanges 18, thereby bringing the rail seat on the same plane with the top of the base member and firmly holding said rail seat in fixed relation to the tie.

The rail seat, flanges and tongues, are preferably formed from heavy sheet metal, as shown in Figs. 6 and 7. The construction shown in Fig. 6 embodies horizontally extending tongues 23 and vertically extending tongues 24, whereby the rail may be securely fixed upon the seat 12, by bending said tongues inwardly, as shown in Figs. 3 and 8. In the modified form shown in Fig. 7, I provide down-turned tongues 25, which engage the rail flanges, for holding the rails upon the seat 13.

It is quite obvious that the rail seat,

2

flanges and tongues may be stamped out of a sheet of metal, at one operation, the several tongues being struck out therefrom; and that it is also quite possible to bend 5 the stamped member into the shape illustrated, without additional manipulation in completing its manufacture.

In order that the tongues 23 and 24 may be quickly and accurately bent into engagement with the rail flange, after the latter is seated, I provide the flanges 18 with apertures 26, for the insertion of any proper tool (not shown) for bracing the flanges against inward or outward movement relative to the rail, while pressing the tongues 23 and 24 into the positions shown.

It is clearly obvious that the base member is additionally protected against breakage by means of the extended end portions 20 of the connecting bars, being securely bolted at both sides of the rail seats. The portions of the connecting bars 10, which lie directly under the rail seats, are perfectly solid and imperforate, and therefore, the tie has 25 greater strength at the points where greater weight or jar occurs.

Thus it will be seen, from the foregoing, that I have provided a rail tie which is capable of attaining the foregoing objects, 30 and in a perfectly practical manner.

I do not limit my invention to the exact details of construction, combination and arrangement of parts described and shown, but my invention may only be limited by a 35 reasonable interpretation of the following claims.

What I claim as new is:

1. In a railroad tie, a concrete base member, a rail seat provided with depending 40 apertured members and tongues adapted to be bent into contact with a rail flange, and anchoring means engaging the apertures, said depending members and anchoring means being embedded within the concrete 45 base member.

2. In a railroad tie, a concrete base member, a rail seat providing substantially vertical side members, tongues thereon adapted to be bent into contact with a rail flange, apertured members depending vertically 50 from said side portions, anchoring means engaging the apertures, said anchoring means and depending members being embedded within the concrete base.

3. In a railroad tie, a concrete base member, a rail seat providing substantially vertical side portions adapted to embrace edges of a rail flange, tongues stamped in said side portion and adapted to be bent inwardly to engage said rail flange, apertured members depending vertically from said side portions and integral therewith, and bent rods adapted to engage said apertured members, said members and rods being embedded 60 in the concrete base.

4. In a railroad tie, a concrete base, a rail seat having a horizontal bottom embedded in the concrete, substantially vertical side walls integral with said bottom and adapted to embrace the edges of a rail flange, tongues 70 stamped in said side walls and adapted to be bent from their lower ends to engage said rail flange, apertured members stamped from the bottom between the side walls and depending vertically therefrom, and embedded 75 in the concrete, and rods engaging opposite depending members, the portions of the rods underlying said bottom being bent downwardly and embedded in the concrete, said side walls provided with openings, whereby an instrument may be inserted for bracing said side walls while said tongues are being bent inwardly.

In testimony whereof I have signed my name to this specification in the presence 80 of two subscribing witnesses.

JAMES PETER DONOVAN.
